TOOTHBRUSH AND PASTE DISPENSER ASSEMBLY

John T. Rodd, Montreal, Quebec, Canada

Application March 12, 1954, Serial No. 415,887

2 Claims. (Cl. 132—84)

This invention relates to toothbrush and paste dispenser assemblies.

An object of the invention is to provide a compact toothbrush and paste dispenser assembly, embodying a toothbrush and a supply of tooth paste, which may be carried in the pocket for ready availability after every meal.

Another object of the invention is to provide a toothbrush and paste dispenser assembly, suitable for carriage in the pocket, in which the brush head is enclosed, when not in use, for purposes of cleanliness and sanitation.

Other objects and advantages of the invention will be apparent from a consideration of the following description in conjunction with the attached drawing, in which:

Figure 1 is a plan view of the assembly of the present invention.

Figure 2 is a view taken along the line 2—2 of Figure 1.

Figure 3 is a plan view of an alternative form of toothbrush and paste dispenser assembly.

Figure 4 is a view taken along the line 4—4 of Figure 3.

Figure 5 is an elevational view of a modified design of the assembly shown in Figures 1 and 2.

Figure 6 is a plan view in section of a modified construction of the assembly of Figure 4, with a portion thereof broken away.

Referring now to the drawing in more detail and particularly to Figures 1, 2 and 5, the reference numeral 1 designates a hollow thimble open at one end and closed at the other end. A toothbrush, including a brush head 2 and a handle 3 connected to the head 2 is arranged so that the brush head 2 is insertable through and withdrawable from the open end of the thimble 1. The handle 3 is detachably engageable with the open end of the thimble 1. The means by which this is accomplished may consist of external threading 4 upon the end of the handle 3 adjacent the brush head 2, as shown in Figure 2, which is engageable with internal threading upon the open end of the thimble 1, or the means may consist of a reduced portion 5 upon the end of the handle 3 adjacent the brush head 2, as shown in Figure 5, which is frictionally engageable within the open end of the thimble 1. When the handle 3 is engaged with the thimble 1 the brush head 2 is held within the thimble 1.

Numerical 6 designates a resilient tube adapted to contain tooth paste, which has a discharge orifice 7 at one end and has the other end 8 open. The open end 8 is exteriorly of and secured to the closed end of the thimble 1. As shown in Figure 2, the end 8 of the tube 6 is internally threaded to engage external threading upon the closed end of the thimble 1. As shown in Figure 5, the open end 8 frictionally engages a reduced projecting portion 9 upon the closed end of the thimble 1. The orifice 7 of the tube 6 is surrounded by an externally threaded neck 10 which is threadably engaged by a detachable cap 11 which closes the discharge orifice 7. A spring clip 12 is secured to the cap 11 and serves as

2

a means for attaching the assembly to the user's pocket. The thimble 1 is provided with ventilating openings 13 to permit air to circulate to the brush head when it is enclosed in the thimble 1.

In the alternative assembly shown in Figures 3, 4 and 6 a resilient tube 14 serves as the handle of a toothbrush and is connected to the head 15 either integrally as shown in Figure 4 or by threaded means 24, as shown in Figure 6. The end of the tube 14 remote from the brush head 15 is open and is closed by a screw plug 16 provided with a turning knob 18.

A passageway 19 extends from the interior of the tube 14 through a portion of the brush head 15 and opens at the base of the bristles 20. A detachable cap 21 covers the brush head 15 and has its open end in frictional engagement with the end of the tube 14 adjacent the brush head 15, which end is reduced slightly to receive the open end of the cap 21. The cap 21 is provided with ventilating openings 22 and a spring clip 23 is secured thereto for fastening the assembly to the user's pocket.

In using the assembly shown in Figures 1, 2 and 5, the assembly is removed from the pocket and the brush detached from the thimble 1. The cap 11 is then removed from the tube 6 and the required amount of tooth paste is deposited upon the brush. After the teeth have been cleaned the brush is returned to its position within the thimble 1 and the cap 11 is reattached to the tube 6. The assembly is then ready to be returned to the pocket until next needed.

In the use of the assembly of Figures 3, 4 and 6, the assembly is detached from the pocket and the cap 21 removed. By pressure now upon the resilient tube 14, a quantity of tooth paste will be supplied directly to the bristles 20 through the passageway 19. After the teeth have been cleaned the cap 21 will be replaced and the assembly reinserted in the pocket.

When the tooth paste carried in the assembly of Figures 1, 2 and 5 is exhausted, the thimble 1 is removed from the end 8 of the tube 6 and the contents of a tube of tooth paste is emptied into the tube 6 through the open end 8. The thimble 1 is then replaced to close the open end of the tube 6. The assembly of Figures 3, 4 and 6 is refilled by removing the plug 16 and refilling the tube 14 with a supply of tooth paste.

The pocket clip 12 in place of being attached to the cap 11, Figures 1, 2 and 5, may be attached to either the handle 3 or the thimble 1.

The cap 21 in place of frictionally engaging the tube 14, Figures 4 and 6, may be attached to the tube 14 by a thread connection.

The tube 14 in place of being threadedly attached to the brush head 15, Figure 6, may be adhesively secured to the head.

If desired, the tube 6 of the form of Figures 1, 2 and 5 or the tube 14 of the form of Figures 3, 4 and 6 may be fabricated of a transparent resilient material.

As will be seen from the foregoing, the present invention provides a convenient and compact case which may be carried clipped to the pocket in the manner of a fountain pen or pencil and which encloses a toothbrush and a supply of tooth paste so that the carrier may brush his teeth at any time wherever he may be. The device is particularly useful for those who must eat a considerable number of their meals away from home and who thus find it inconvenient to brush their teeth after each meal without the assistance of a device such as that of the present invention.

What is claimed is:

1. A toothbrush and paste dispenser assembly comprising a hollow thimble open at one end and closed at the other end, a toothbrush including a brush head and a handle connected to said head arranged so that the brush

head is insertable through and withdrawable from the open end of said thimble, the handle having a portion provided with external threads in threaded engagement with internal threads formed on the portion of said thimble inwardly of the open end thereof for holding the brush head of the toothbrush within said thimble, a resilient tube adapted to contain toothpaste and having a discharge orifice in one end and having the other end open arranged so that the open end of said tube is exteriorly of and threadably engages the portion of said thimble adjacent the closed end of said thimble.

2. A toothpaste and brush dispenser assembly comprising a hollow thimble open at one end and closed at the other end, a toothbrush including a brush head and a handle connected to said head arranged so that the brush head is insertable through and withdrawable from the open end of said thimble, the handle having a portion provided with external threads in threaded engagement with the internal threads on the portion of said thimble inwardly of the open end thereof for holding the brush head of the toothbrush within said thimble,

a resilient tube adapted to contain toothpaste having a discharge orifice in one end and having the other end open arranged so that the open end of said tube is exteriorly of and threadably engages the portion of said thimble adjacent the closed end of said thimble, and a detachable cap closing the discharge orifice of said tube.
